[57] CLAIM

The ornamental design for a head for stringed instruments, as shown and described.

DESCRIPTION

FIG. 1 is a perspective view of a head for stringed instruments showing my new design;

FIG. 2 is an end view in elevation thereof;

FIG. 3 is a side view in elevation thereof;

FIG. 4 is a top plan view thereof;

FIG. 5 is a side elevation view opposite of that shown in FIG. 3; and,

FIG. 6 is a bottom plan view thereof.

The broken line showing of a fragmentary neck portion is for illustrative purposes only and forms no part of the claimed design.
